IRONING MACHINE

George W. Wardwell, Jr., Nichols, and George J. Filla, Bridgeport, Conn., assignors to General Electric Company, a corporation of New York

Application December 19, 1936, Serial No. 116,724

13 Claims. (Cl. 38—59)

The present invention relates to ironing machines of the type having a heated shoe which cooperates with a roll.

The object of our invention is to provide an improved construction and arrangement in ironing machines of this type and for consideration of what we believe to be novel and our invention, attention is directed to the accompanying description and the claims appended thereto.

In the accompanying drawings, Figure 1 is a perspective view of an ironing machine embodying our invention; Figure 2 is an end elevation of the ironing machine, partly broken away; Figure 3 is a sectional view taken on line 3—3 of Figure 2; Figure 4 is a side elevation, in section, along line 4—4 of Figure 2, and broken away to show the constructions for supporting the roll and the shoe; Figure 5 is an end elevation of the roll with the roll retaining washer removed; Figure 6 is a sectional view taken on line 6—6 of Fig. 4; Figure 7 is a sectional view taken on line 7—7 of Fig. 4; Figure 8 is a sectional view taken on line 8—8 of Fig. 4; Figure 9 is a top plan view, partly broken away of the hinged support for the shoe; Figure 10 is a sectional view taken on line 10—10 of Fig. 4; Figure 11 is an exploded perspective view of the mechanism for driving the roll and for moving the roll toward and away from the shoe; Figure 12 is a side elevation, partly in section on lines 12—12 of Fig. 15, of a modification; Figure 13 is a view showing another arrangement for supporting the roll; Figure 14 is a top plan view, partly broken away, of the arrangement for supporting the shoe used in the ironing machine shown in Fig. 12; and Figure 15 is an end elevation of the ironing machine shown in Fig. 12.

Referring to the drawings, the ironing machine comprises a frame or housing 1 which carries a roll 2, a shoe 3, and the driving mechanism for rotating the roll and for moving the roll toward and away from the shoe. The housing is provided with a flange 4 for supporting the ironing machine on the top of a suitable table 5.

The housing has a vertical hollow portion 6 which serves as the frame or outer casing for the electric motor used to drive the ironing machine. The stationary member 7 of the electric motor is pressed into the hollow portion 6 and the rotary member 8 of the electric motor is supported on a shaft 9 the upper end of which is journaled in bearing 10 carried in a web 12 and the lower end of which is journaled in a bearing 13 carried in a bearing housing 14 threaded into the lower end of the hollow portion 6. The bearing

housing 14 carries a thrust ball 15 which supports the shaft 9. The web 12, which is integral with the housing, forms a closure for the upper end of the electric motor.

The motor shaft 9 projects above the bearing 10 and on its projecting end is cut a worm 16 which meshes with a worm wheel 17. The worm wheel 17 is rotatably supported on a shaft 18 which rotates in a bearing 19 in a tube 19. The tube 19 is pressed into or otherwise fixed in a boss 20 in the side wall of the housing 1. Integral with the worm wheel 17 is a pinion 21 which meshes with a gear 22 rotatably carried on a crank 23. When the gear 22 is in the position shown in Figs. 2 and 11, it meshes with a gear 24 fixed to a shaft 25 which is journaled in boss 26. The crank 23 is integral with a shaft 27 which is rotatably carried in the side walls of the ironer housing. The left end of the shaft 27 projects outside the housing (see Fig. 3) and has formed thereon a gear 28 which meshes with a segmental gear 29. The segmental gear is integral with a lever 30 which is pivoted at 31 on the ironer housing. When the lever 30 is pivoted downward from the position shown in dotted lines in Fig. 2, the shaft 27 is turned, thereby moving the gear 22 away from the pinion 21 and breaking the driving connection between the continuously rotating pinion 21 and the gear 24. The shaft 25 is used to drive the roll in a manner which will be hereinafter described and the lever 30 therefore controls the driving connection to the roll. A thrust plate 30^a is arranged between the housing and the adjacent faces of gears 21, 22 and 24. It is provided with an enlarged opening 30^b (Fig. 3) to permit movement of the crank 23.

The construction of the roll 2 is shown in detail in Figs. 4 and 11. It comprises a sheet metal cylinder 32 having a pad 33 on its outer surface. The pad 33 is held in place by a pad cover 34, the ends of which are secured to the inner periphery of the cylinder 32 by snap rings 35. On either side of a center line slightly to the right of the center of the roll are two disks 36 having outwardly projecting flanges 37 fixed to the interior of the cylinder 32 and having inwardly extending flanges 38 which are fixed to a bearing sleeve 39. The bearing sleeve 39 bears on a sleeve 40 which is rotatably supported by an eccentric 41 journaled on the left end of the tube 19. Endwise movement of the roll off the eccentric is prevented by a retaining washer 41^a mounted on a projection 41^b on the eccentric. The eccentric 41 is fixed to the shaft 18 so that

the bearing between the eccentric 41 and the outside of the tube 19 also serves to support the left end of the shaft 18. As the shaft 18 is turned it is obvious that the roll will be moved laterally with respect to the tube 19. This lateral movement of the roll with respect to the tube 19 is used to move the roll toward and away from the shoe and is also used to complete the driving connection to the roll by moving an internal gear 42 which is carried by the roll into mesh with a pinion 43 fixed to the shaft 25. The gear 42 and pinion 43 are arranged to be in mesh when the roll is pressed against the shoe and to be out of mesh when the roll is moved away from the shoe. Thus when the roll is pressed against the shoe it is rotated and feeds the material being ironed under the shoe. The teeth on the gears 42 and 43 mesh before full pressure is developed between the roll and the shoe so that the starting load on gear teeth is reduced.

As the gear 42 is moved into mesh with the pinion 43, there is a tendency for the teeth to jam. This tendency is increased by the fact that the gear 42 is an internal gear, with its teeth extending radially inward, and the pinion 43 is an external gear, with its teeth extending radially outward. It is, therefore, possible for a pair of teeth on the pinion 43 to straddle a pair of teeth on the gear 42, in which case further approach of the gears would result in serious jamming. This tendency to jamming of the gear teeth is prevented by providing sufficient clearance between the bearing sleeves 39 and 40 so that the roll can have a slight tilting movement. When the gear teeth strike, the pressure exerted on the teeth of gear 42 causes the roll to be tilted to move the teeth on the gear 42 away from the teeth on the pinion 43. During this tilting, the rotation of the pinion 43 causes its teeth to be moved to a position in which the teeth will not jam as they mesh. From one aspect the tiltable mounting of the roll can be regarded as a yielding mounting for the gear 42 so that as the gear is moved toward the pinion 43 it can yield to prevent jamming of the gear teeth.

The eccentric 41 is provided with a pocket 41^c which contains grease for lubricating the bearing surface between the eccentric and the tube 19, the bearing surfaces between the eccentric and the sleeve 40, and the bearing surfaces between the sleeve 40 and the sleeve 39. The grease is fed to the bearing surfaces through holes 41^d (see Fig. 4) in the sleeve 40 and in the eccentric.

The bearing sleeve 39 which rotatably supports the roll is located slightly to the right of the center of the roll as viewed in Fig. 4 so that when the roll is pressed against the shoe, the pressure exerted by the shoe on the roll tends to pivot the roll about the bearing sleeve 39 in a counter-clockwise direction as viewed in Fig. 4 and therefore tends to hold the internal gear 42 in mesh with the pinion 43. In order to prevent jamming of the gear teeth due to too great a movement of the gear 42 toward the pinion 43, a collar 44 is fixed to the internal gear 42 which is adapted to engage a collar 45 on the shaft 25 and limit the movement of the gear 42 toward the pinion 43. The collars 44 and 45 are of the same diameter as the pitch lines of the gear teeth on the respective gears.

As described above the rotation of the shaft 25 is controlled by the lever 30 which moves the gear 22 away from the pinion 21, breaking the driving connection to the shaft 25 on which the pinion 43 is fixed. By the manipulation of the

lever 30 it is therefore possible for the roll to remain stationary when pressed against the shoe. This is desirable when the ironing machine is used for pressing.

- 5 The roll is moved toward and away from the shoe by an arrangement for coupling the shaft 18 to the worm wheel 17 so that the shaft is rotated in steps of 180 degrees. The particular arrangement shown comprises an arm 46 pinned to the shaft 18 which is provided with radial slots in which are slidably carried clutch keys 47. The keys 47 are urged outwardly by springs 48 and the outward movement is limited by the flanges 49 on a plate 50 fixed to the arm 46. When the keys are in the inner position shown in Fig. 3 there is no connection between the worm wheel 17 and the shaft 18. When moved outward, the keys cooperate with notches 51 in a flange on the worm wheel to complete a driving connection from the worm wheel to the shaft 18. An odd number of notches are provided so that when one of the keys 47 fits into one of the notches 51 the other key is held in its inner position by one of the teeth 52 between the notches. When the parts are in the position shown in Fig. 2 the upper key 47 is held in its inner position by a lever 53 which is pivoted at 54 on the flange 67 of a bracket 55 fixed to the housing and which is pulled by a spring 56 against the key. A stop 53^a limits the movement of the lever 53 by the spring. 25 The lever 53 is provided with a flange 57 which engages the arm 46 and prevents movement of the arm in a counter-clockwise direction as viewed in Fig. 2. The lower key 47 is held in its inner position by engagement with a trip lever 58 which is carried on the upper end of rock shaft 59 journaled on the ironer housing. The linkage for operating the trip lever is shown in Fig. 11. It comprises a lever 60 pivoted at 61 on the under side of the table and urged by a spring 62 against a stop 63. The lever 60 is provided with a knee pad 64 so that the lever can be operated by a sidewise motion of the operator's knee. The lever 60 is connected by means of a link 65 to a crank 66 fixed to the rock shaft 59. It is thus apparent that when the knee pad 64 is moved to the right (Fig. 11) the shaft 59 will be pivoted in a counter-clockwise direction thereby moving the trip lever 58 away from the lower key 47 and permitting the spring 48 to force it outward into engagement with one of the notches 51, thus completing a driving connection from the worm wheel 17 to the shaft 18. This key will now be termed the driving key. As soon as this driving connection is completed the lever 60 may be released and it will be returned to its normal position by the spring 62. When the driving key is moved into one of the notches 51, the other key 47 is held in its inner position by one of the teeth 52. This is due to the fact that the number of notches 51 is odd. The worm wheel rotates in a clockwise direction as viewed in Fig. 2. After the first few degrees of rotation of the shaft 18, the upper key 47 is clear of the lever 53, and the lever is held against the stop 53^a by the spring 56. As rotation of the shaft 18 nears 180 degrees, the arm 46 strikes the lower edge of the flange 57 on the lever 53 and moves the lever 53 in a counterclockwise direction as viewed in Fig. 2. When the shaft 18 has rotated through 180 degrees the driving key is moved out of the notch 51 by engagement with the flange 67 on the bracket 55, thus, breaking the driving connection to the shaft 18. At this time, the arm 46 is clear of the lower edge of

the flange 57, and the lever 53 is moved to the position shown in Fig. 2 in which the flange 57 prevents counter-clockwise movement of the shaft 18. The tendency to counter-clockwise movement of the shaft 18 may be due to the breaking of the driving connection to the shaft before the eccentric reaches dead center as the roll is pressed against the shoe, or to the tendency of the roll to turn due to the eccentric pivoting thereof on the tube 19. From one aspect, the flange 57 is a cam which positively moves the driving key out of the slot 51. After the key is moved out of the slot, it is moved to the inner position by the lever 53. The spring 56 is not strong enough to move the driving key out of the notch 51 but is strong enough to move it inward against the force of the spring 48 after it has been moved out of the notch 51 by the flange 57. The purpose of the lever 53 is to prevent the key remaining in a position so close to the slots 51 that it continually clicks against the teeth 52. The lever 53 is therefore in the nature of a follow up device to increase the spacing of the driving key from the notches 51. At this time, if the lever 60 has been released, the lever 58 will occupy a position in which it will hold the other key in its inner position. It is thus apparent that for each actuation of the lever 60 the shaft 18 and the eccentric 41 connected thereto will be turned through 180 degrees. If the lever 60 is continuously held to the right, the shaft 18 will be rotated continuously, the driving connection to the shaft being completed successively by each of the keys 47.

The trip lever 58 has an upturned end 58^a which serves as a stop to limit the movement of the arm 46 in a clockwise direction as viewed in Fig. 11. This tendency to clockwise movement of the arm 46 may come from overtravel of the shaft 18 due to inertia, from friction between the arm 46 and the worm gear 17, or from the pressure exerted on the roll by the shoe if the eccentric is moved slightly past dead center when the roll is pressed against the shoe. The stop 58^a is a precautionary device which is normally not brought into use.

It is desirable that the movement of the roll toward and away from the shoe be effected without rotating the roll. This is accomplished by providing the intermediate sleeve 40 between the eccentric and the sleeve 39 and by providing a tongue 68 on the sleeve 40 which fits in a radial slot 69 in a disk 70. The disk 70 is secured to the tube 19 by set screws as shown in Figs. 8 and 11. The radial slot 69 is located so that as the eccentric is rotated the roll is moved directly toward and away from the shoe without any substantial turning movement. As the roll moves toward the shoe, the tongue 68 slides in the slot 69. The movement of the sleeve 40 and the roll carried thereby can best be described as a pivotal movement about the tongue 68. During the first part of the movement the sleeve 40 is pivoted about tongue 68 in a counter-clockwise direction, as viewed in Fig. 11, until the eccentric has turned 90 degrees from the position shown. During the next 90 degrees of turning of the eccentric, the sleeve 40 is pivoted in a clockwise direction about the tongue 68. The roll has the same movement as the sleeve 40 until it contacts the shoe at which time such movement is prevented by the friction between the roll and the shoe and by the completion of the driving connection to the roll which starts the rotation of the roll. While moving towards the shoe, the roll is swung up-

wardly about tongue 68 during the first quarter of the movement of the eccentric and then swung downwardly about tongue 68 during the second quarter of the movement of the eccentric into engagement with the shoe. While moving away from the shoe, the roll is first swung downwardly about the tongue 68 during the first quarter of the movement of the eccentric and then upwardly about the tongue 68 during the second quarter of the movement of the eccentric. During the movement of the roll toward the shoe, the roll appears to be first lifted and then moved downward into engagement with the shoe. During the movement of the roll away from the shoe, the roll appears to be first lowered and then raised. If the direction of rotation of the eccentric were reversed it is apparent that during the movement of the roll toward the shoe, the roll would first be lowered and then lifted into engagement with the shoe and that during the movement of the roll away from the shoe the roll would first be lifted and then lowered. It is obvious that by changing the shape of the slot 68 the movement of the roll may be varied.

The shoe 3 comprises an arcuate metal plate 70^a which is heated by suitable electric heating units (not shown). On the upper surface of the plate 70^a are secured a pair of studs 71 which extend through the web 72 of a channel-shaped bracket 73. The bracket 73 is clamped to the plate 70^a by sleeves 74 around the studs, and a cover plate 75 is clamped between the upper ends of the sleeves 74 and nuts 76 threaded on the studs. The flange 73^a of the bracket 73 is provided with round holes (not shown) and the flange 73^b of the bracket is provided with elongated slots 77 (see Fig. 10) through which extend arms 78. Endwise movement of the shoe on the arms 78 is prevented by pins 78^a. A leaf spring 79, arranged on the stud 71 adjacent the flange 73^b and between the under side of the arms 78 and the upper side of the web 72 biases the shoe downward so that the arms 78 normally rest against the upper ends of the slots 77 and the shoe is held parallel to the roll. When the roll is pressed against the shoe the shoe pivots about the openings in the flange 73^a until the pressure on the shoe is equalized. With this support it is obvious that the shoe can tilt in all directions about axes in the plane of and passing through the center of the shoe, thus equalizing the pressure at all parts of the shoe. Clearance holes 79^a are provided in the shoe cover to permit tilting of the shoe. Another advantage of the shoe support is that the greater portion of the arms 78 is concealed beneath the shoe cover 75. The arms 78 are preferably chosen to have sufficient resilience so that they serve to limit the pressure between the roll and the shoe to a safe value to allow for variation in thickness of the padding and of the material being ironed.

The arms 78 are fixed in a hinge member 80 carried on a pin 80^a in boss 82 on the upper end of the ironer housing. The hinge member is normally held in a fixed position by a pin 81 which is slidably carried in bosses 82 and 83 and is urged by a spring 84 into a recess 85 in the hinge member. The pin 81 is provided with a knob 86 by means of which the pin can be pulled out of the recess 85. When this is done the shoe may be pivoted away from the roll. This movement permits the shoe to be cleaned and also serves to release the pressure between the roll and the shoe in case the power supply should fail while the roll was pressed against the shoe.

Operation

In the use of the ironer the material to be ironed is arranged on the roll. The lever 60 is then moved to the right as viewed in Fig. 11 by pressure exerted on the knee pad 64, moving the trip lever 58 away from the adjacent key 47. The spring 48 moves the key 47 outward into one of the notches 51 in the continuously rotating worm wheel 17 thus completing a driving connection from the worm wheel 17 to the shaft 18. This key will now be termed the driving key. The pressure on the knee pad 64 may now be released, and the trip lever 58 will be returned to its normal position by the spring 62. The shaft 18 rotates through 180 degrees at which time the driving key is pushed inward to disengage the driving connection by engagement with the flange 67 on the bracket 55. Since the lever 58 has now been returned by the spring 62 to the position shown in Fig. 11, the other key 47 is held in its inner position by the lever 58. Rotation of the shaft 18 through an angle of 180 degrees from the position shown in Fig. 11 will turn the eccentric 41 through 180 degrees, thus pressing the roll against the shoe and completing a driving connection to the roll by moving the gear 42 into mesh with the pinion 43. When the ironing operation is completed the lever 60 is again pushed to the right and the shaft 18 is rotated through 180 degrees in the manner described above. At the end of this movement the roll is away from the shoe and the parts occupy the position shown in Fig. 11.

If the ironer is to be used for pressing, the lever 30 is moved downward from the position shown in dotted lines in Fig. 2, moving the gear 22 out of mesh with the pinion 21. This breaks the driving connection to the pinion 43 so that the roll is not rotated when the gear 42 is moved into mesh with the pinion 43.

In Fig. 13 is shown a slightly different construction for supporting the roll. In this construction the roll is supported on a tube 81 which is pressed into or otherwise fixed in a boss 88 on the ironer housing. At each end of the roll are eccentrics 89 and 89^a which are rotatably supported on the tube. The eccentrics are connected by a tube 90 which is concentric with the tube 81. The eccentrics rotatably support the roll bearings 91 which are carried in sleeves 92 secured respectively to flanges 93 and 93^a on rings 94 and 94^a secured to the inner surface on the roll casing 32. Sufficient clearance is provided between the eccentrics and the bearings 91 so that the roll can have a tilting movement to prevent clashing of the driving gears for the roll. The roll is held on the eccentrics by a retaining washer 94^b threaded on a stud 94^c on the eccentric 89. As in the previously described construction the eccentrics are turned by the shaft 18 which extends through the tube 81. The shaft 18 is secured to the eccentric 89. The driving connection to the roll is effected in the same manner as in the previously described construction, by means of an internal gear 95 which is fixed to the flange 94^a and which is moved into and out of mesh with the continuously driven pinion 43 fixed on the shaft 25. These gears are so arranged that they are in mesh when the roll is pressed against the shoe and are out of mesh when the roll is moved away from the shoe.

In Figures 12, 14 and 15 is shown another modification of the ironing machine. In this construction the housing 96 which contains the driv-

ing mechanism for the ironer is provided with an integral tubular projection 97 which projects within the roll. The driving mechanism contained within the housing is identical with that shown in Figures 2, 3, and 11, the corresponding parts being indicated by the same reference characters. The roll is likewise of the same construction as that shown in the previously described ironer. At the center of the roll are secured rings 98 and 99 having, respectively, inwardly extending flanges 100 and 101 secured to a sleeve 102 carrying a bearing 103. The bearing is rotatably supported on an eccentric 104 which is journaled on a hub 105 at the end of the tubular projection 97. There is sufficient clearance between the eccentric and the hub 105 so that the roll can tilt and can also have a slight bodily movement relative to the hub. A spring-pressed friction pin 106 carried by the eccentric bears on the hub 105 and holds the roll straight and steady when away from the shoe. The eccentric is connected to the shaft 18 by means of an arm 107 having a pin 108 fitting in a hole in the eccentric. The arm 107 is connected to the shaft 18 by means of a pin 109 fixed to the shaft which fits in notches 110 in the arm. The arm 107 is slideable on the shaft and is held in the position shown by a spring 111 arranged between the end of the arm and a washer 112 on the shaft. The arm 107 is pinned to a tubular sleeve 113 which is provided with a handle 114 adjacent the end of the roll. When the parts are in the position shown, the shaft 18 is connected to the eccentric 104. By pulling on the handle 114, the notches 110 in the arm 107 may be moved clear of the pin 108 in which case the eccentric may be turned by means of the handle 114 since the pin 108 will still fit in the hole in the eccentric. This construction provides an alternative means for turning the eccentric in case of a failure of the power supply which would prevent the turning of the shaft 18 by means of the motor drive.

The shaft 18 is rotated in successive steps of 180 degrees by means of the driving mechanism shown in Figs. 2, 3, and 11. When the shaft is in the position shown, the roll is spaced from the shoe. When the shaft has been turned through 180 degrees from this position the roll is moved by the eccentric against the shoe. This movement of the roll completes the driving connection to the roll by bringing an internal gear 115 carried by the ring 99 into mesh with a pinion 116 carried on the continuously driven shaft 25. The driving connection to the roll is, therefore, effected by the movement of the roll toward the shoe. When the roll is moved away from the shoe this driving connection is broken. The clearance between the eccentric 104 and the hub 105 permits a tilting and bodily movement of the roll relative to the hub 105 which tends to prevent clashing of the gears 115 and 116 as they are moved into mesh. That is, if the teeth of the internal gear 115 are in line with the teeth of the pinion 116, the pressure exerted on the teeth of the internal gear causes the internal gear to be moved away from the pinion. During this movement of the internal gear, the pinion, which is continuously rotating, turns to a position in which the teeth will not jam as they mesh. The tilting movement of the roll also helps align the roll with the shoe so that uniform pressure is obtained throughout the surface of contact between the roll and the shoe. This tilting does not materially affect the mesh of the gears 115 and 116 since these gears are located close to

the eccentric and the tilting, therefore, is accompanied by a relatively small radial movement of the teeth of the gear 115.

The shoe 3 is of the same construction as that shoe in Fig. 4 and is supported in the same manner on a pair of rods 117 and 117^a. The rods 117 and 117^a extend through openings in the side walls of the housing 96. The rod 117^a is shorter than the rod 117 and its end fits in a recess 118 in a boss 119. The rod 117 fits in a recess 120 in a boss 121. The rod 117 is provided with an annular groove 122 into which extends a pin 123 carried by a leaf spring 124. The pin 123 prevents longitudinal movement of rod 117 and thereby holds the rods 117 and 117^a in a fixed position relative to the housing 96. When the pin 123 is lifted clear of the groove 122 the shoe may be moved endwise until the rod 117^a is clear of the housing 96. The shoe may then be pivoted about the rod 117 which is still journaled in the housing. This makes possible the movement of the shoe to a position in which its work contacting surface may be easily cleaned. The complete removal of the shoe from the housing is prevented by means of a snap ring 125 which prevents the removal of the rod 117. From one aspect, the rods 117 and 117^a can be considered as providing a hinged mounting for the shoe.

The above described clearance between the roll and eccentrics 41, 89, 89^a, and 104 to provide a yieldable support for the internal gears 42, 95, and 115 and prevent jamming of the internal gears with the pinions 43 and 116 is the sole invention of the applicant Wardwell and is being claimed in his application Serial No. 134,850.

What we claim as new and desire to secure by Letters Patent of the United States is:

1. In an ironing machine, a shoe, a hollow roll, an arm extending within the roll, an eccentric pivoted on said arm, a bearing rotatably carried by said eccentric, said bearing rotatably supporting the roll, means for turning the eccentric on said arm whereby the roll is moved relative to the shoe, and means preventing a frictional driving connection between the eccentric and the roll whereby rotation of the roll by the eccentric is prevented.

2. In an ironing machine, a shoe, a hollow roll, an arm extending within the roll, an eccentric pivoted on said arm, a bearing rotatably carried by said eccentric, said bearing rotatably supporting the roll, means for turning the eccentric on said arm whereby the roll is moved relative to the shoe, and a member carried by said arm having a pin and slot connection with the bearing for restricting turning of the bearing.

3. In an ironing machine, a shoe, a hollow roll, an arm extending within the roll, a bearing rotatably supporting the roll, eccentric means carried on said arm for moving said bearing whereby the roll is moved toward and away from the shoe, said eccentric means having a tendency to turn the bearing, and means engaging said bearing for decreasing the tendency of turning of the bearing.

4. In an ironing machine, a shoe, a hollow roll, a frame, an arm supported by the frame and projecting within the roll, means including bearing means for rotatably supporting the roll and for permitting tilting of the roll about an axis transverse to the axis of the roll, said bearing means being located centrally within the roll and being pivoted eccentrically on said arm whereby the roll is moved toward and away from the shoe by pivotal movement of said bearing means,

an internal gear carried by the roll adjacent the frame, a shaft carried by the frame having a driving pinion fixed thereto, the position of said driving shaft being such that the driving pinion is in mesh with said internal gear when the roll is pressed against the shoe and is out of mesh with said internal gear when the roll is moved away from the shoe, and cooperating bearing surfaces on said roll and said shaft for limiting tilting of the roll under pressure of the shoe.

5. In an ironing machine, a shoe, a hollow roll, a frame having a tubular portion projecting therefrom within the roll, bearing means rotatably supporting the roll, said bearing means being located centrally within the roll and being pivotally and eccentrically carried on the tubular portion of the frame whereby the roll is moved toward and away from the shoe by pivotal movement of said bearing means, an internal gear carried by said roll adjacent said bearing means, and a drive shaft projecting within and journaled in the tubular portion of the frame and having a driving pinion fixed thereto, said pinion meshing with said internal gear when the roll is pressed against the shoe and being out of mesh with said internal gear when the roll is moved away from the shoe.

6. In an ironing machine, a hollow roll, a frame, an arm supported by the frame and projecting within the roll, bearing means rotatably supporting the roll, said bearing means being carried on said arm, means providing a tiltable support for the roll permitting tilting of the roll about an axis within the central part of the roll and transverse to the roll axis, a shoe, power means for moving said bearing means laterally with respect to said arm whereby the roll is moved toward and away from the shoe, a driving pinion carried by the frame, and a gear carried by the roll and moved into and out of mesh with the pinion by the lateral movement of the roll, said tiltable support for the roll permitting movement of said gear whereby jamming of the gear teeth is prevented.

7. In an ironer, a shoe, a hollow roll, a frame at one end of the roll having gearing for driving the roll, eccentric means within the roll for moving the roll toward and away from the shoe, a shaft having a disconnectible connection with said gearing for operating said eccentric means, a handle at the end of the roll opposite said gearing, means for disconnecting said eccentric means from said shaft, and means for connecting said handle to said eccentric means whereby the eccentric means may be operated by said handle independently of said shaft.

8. In an ironer, a shoe, a hollow roll, a frame at one end of the roll having gearing for driving the roll, eccentric means within the roll for moving the roll toward and away from the shoe, a shaft having a disconnectible connection with said gearing for operating said eccentric means, a handle at the end of the roll opposite said gearing, means operated by said handle for disconnecting the eccentric means from said shaft, and means for connecting said handle to said eccentric means whereby the eccentric means may be operated by said handle.

9. In an ironing machine, a roll, an eccentric having an axis of rotation extending along the axis of the roll, a bearing rotatably carried by and frictionally bearing on the eccentric, said bearing rotatably supporting the roll, means for turning the eccentric whereby said roll and roll supporting bearing are bodily moved with respect

to the axis of the eccentric, and means engaging the bearing for restricting rotation of the bearing by the eccentric.

10. In an ironing machine of the type having a roll movable toward and away from a shoe, a frame at one end of the roll, a pair of arms supported wholly at one end by said frame and extending along the roll for supporting a shoe, a pivotal support for one of said arms, means holding the other of said arms stationary for preventing pivotal movement of the first arm whereby the shoe is held in a fixed position relative to the roll, and means for releasing said other arm whereby the shoe may be swung away from the roll.

11. In an ironing machine of the type having a roll movable toward and away from a shoe, a frame at one end of the roll, a pair of arms supported wholly at one end and extending lengthwise along the roll, and means for tiltably supporting a shoe on said arms comprising a flange located centrally on the shoe and having openings therein loosely fitting over said arms.

12. In an ironing machine of the type having a roll movable toward and away from a shoe, a frame at one end of the roll, a shoe having a heated metal plate cooperating with the roll and a cover spaced therefrom, and a shoe supporting arm supported at one end from said frame and secured at the other end to the shoe, said arm extending between said cover and said plate whereby the greater portion of its length is concealed.

13. In an ironer of the type having a roll movable toward and away from a shoe, a frame at one end of the roll, a shoe having a metal plate for contacting the roll and having a cover spaced therefrom, an arm extending from the frame lengthwise of the roll between said plate and said cover and having its free end centrally within said shoe, and means between said plate and said cover for supporting the shoe on the end of said arm.
